E. L. HILL

DOOR CLOSER

Filed August 18, 1924

INVENTOR
Ernest L. Hill

BY *M. C. Frank*
ATTORNEY

UNITED STATES PATENT OFFICE.

ERNEST L. HILL, OF JACKSONVILLE, FLORIDA.

DOOR CLOSER.

Application filed August 18, 1924. Serial No. 732,710.

To all whom it may concern:

Be it known that I, ERNEST L. HILL, a citizen of the United States, residing at Jacksonville, in the county of Duval and 5 State of Florida, have invented certain new and useful Improvements in Door Closers, of which the following is a specification.

The present invention relates to door closers, and of the type that employs a 10 spring to effect the closing of the door.

The major objects of the invention are to design and construct it for refrigerator service primarily, although it may be used wherever advantageous. The salient features of the invention include a powerful and confined coiled spring of special form, adapting the marketable device to be used on a right or left-hand door; a housing of simple form to accommodate the above 15 reversible spring; and a unique sprocket device for enabling the door to remain open and out of contact with the closer-arm of the invention, when it is desired to refill the refrigerator, or the like, as in a butcher 20 shop or meat packing establishment.

The invention possesses other advantageous features, some of which, with the foregoing, will be set forth at length in the following description where I shall outline in 30 full that form of the invention which I have selected for illustration in the drawings accompanying and forming part of the present specification. In said drawings I have shown one form of my invention, but it is to be understood that I do not limit myself 35 to such form, since the invention, as expressed in the claim, may be embodied in a plurality of forms.

Referring to said drawings:

40 Figure 1 is a top view of the closer in service, and shown applied to a left-hand door. The cover of the housing has been removed to show the inclosed parts in assembly.

45 Fig. 2 is a front elevation of Fig. 1. Parts of the device are shown in section for clarity.

50 Fig. 3 is a top view of the completed article. The dot-and-dash lines radiating from the shaft represent the arm held out of contact with the door.

Fig. 4 is an elevation of the shaft for the closer, and Fig. 5 an elevation of the spring.

I will now describe the figures in detail: 55 The numeral 6 indicates a door which may

be hinged to the jamb 7 in the usual way. 8 is a housing preferably of cast metal, having a closed bottom 9 and an open top; to the side of the housing a bracket 10 is formed adapted to receive screws 11, or the like, for securing the device to the jamb. In 60 the bracket and communicating with the interior of the housing, a T-shaped slot 12 is formed for a purpose to be later described.

13 is a coil of spring steel and rather tightly wound at the outside coils, and is embraced by a strip 14 riveted as at 15, to form a ring to constrain the spring to a size less than the diameter of the opening in the housing 8, so that the spring may be easily 65 set therein and in unbinding relation therewith. The interior coils of the spring are wound in unstressed relation with respect to the spring, but are stressed when in service. The terminals of the spring are formed with 70 hooks 16 and 17. Hook 16, the outer one, has had a portion cut away, Fig. 5, for the unobstructed passage of the strip 14. This hook is adapted to engage the T-slot 12, 75 Fig. 1, for anchorage to the stationary member of the closer. The other hook 17, the inner one, engages a slot 18 in the rotatable shaft 19.

20 is the cover for the housing 8, and is secured thereto by any suitable means, such as machine screws 21. The cover has a boss 22 for centrally supporting a sprocket bushing 23, and which bushing has a central opening for the reception and support of the shaft 19. The shaft is here shown hexagon 25 in shape, and the bushing-opening registers therewith. The lower part of the shaft is cylindrical, and registers with its bearing 24 in the bottom 9 of the housing 8, Fig. 2. The boss 22 forms the upper bearing for the 30 sprocket bushing and shaft.

Around the shaft and in the center of the coil is a cylindrical bushing 25, having a registering slot 26 for the spring-hook 17, to enable the spring in operation to be 35 wound around a cylinder rather than the comparative small diameter of the hexagon shaft with its sharp edges.

The arm 27 for closing the door is a common one employed in devices of this character, but I prefer to make the same forked as at 28, Fig. 2, to carry any suitable roller 40 29, the latter operating on a track 30, such as light channel iron secured to the door 6 as by screws 31. The opposite end 32 of 45

the arm is adapted to slip over the shaft 19 and be supported thereon, and also on the sprocket 23.

On the center line of the cover 20 is pivotally secured the pawl 33 by the machine screw 34. The pawl is used as a ratchet to tension the spring 13 previous to positioning the arm 27 on the shaft 19 for service against the door, and after such tensioning the pawl 10 may be pushed out of engagement to the position shown in dot-and-dash lines, Fig. 3. Also the pawl is brought into service when it is desired to leave the door remain open; this may be accomplished by opening the 15 door the desired angle, and bringing the pawl into engagement with the corresponding tooth of the sprocket, the pawl serving as a stop to absorb the spring reaction, thus holding the arm out of active contact with 20 the door. The teeth of the sprocket are long, and the end of the pawl so curved as to be pushed from disengagement by turning the arm from the pawl, the following tooth pushing the pawl away.

25 The letters L and R on the cover signify "left" and "right" for indicating purposes in the attachment of the device to a door. The drawings throughout show a "left-hand" assembly; but for the opposite-hand use and 30 assembly, simply reverse the spring 13 by engaging the hook 16 thereof to the opposite side of the T-shaped slot 12, and move the pawl 33 to the opposite or R side of the cover 20.

35 Having thus described the preferred form

of my invention, what I claim as new and desire to secure by Letters Patent of the United States, is the following:

A door closer comprising, a cup-shaped housing having a closed bottom, a bracket 40 on said housing for securing the housing to a door frame member and a slot formed in the bracket, a cover for the housing, a coil spring for the housing having its terminals formed into hooks, the outer hook having a 45 portion cut away, a ring encircling the spring and passing through the cut-away portion for constraining the spring to a less diameter than the inside diameter of the housing, a slotted central shaft in the housing, one end of said shaft projecting through the cover and the opposite end terminating within the housing, and an arm for engagement with the shaft; the outer hook of the spring adapted to engage the slot in the 50 bracket and the inner hook the slot in the shaft, the arm adapted to turn the shaft to coil the spring, and the said device when secured to a door jamb adapted to close the door, and the said cover provided with a 55 centrally supported sprocket and a pawl to engage the sprocket, to hold the said arm out of contact with the door when desired, and the said slot in the bracket formed T-shaped to adapt the said spring to be set in 60 reversed position in the housing to cause the said arm to operate on a door pivoted to swing in the opposite direction.

In testimony whereof I affix my signature.

ERNEST L. HILL.
